UNITED STATES PATENT OFFICE.

JAMES E. HAWKINS, OF GLENDALE, CALIFORNIA.

REFRIGERATOR.

1,328,625.

Specification of Letters Patent. Patented Jan. 20, 1920.

Application filed August 8, 1919. Serial No. 316,113.

To all whom it may concern:

Be it known that I, JAMES E. HAWKINS, a citizen of the United States, residing at Glendale, in the county of Los Angeles and State of California, have invented certain new and useful Improvements in Refrigerators; and I do hereby declare the following to be a full, clear, and exact description of the invention, such as will enable others skilled in the art to which it appertains to make and use the same.

The present invention relates to a refrigerator or food-storage compartment, and aims to provide such a device of novel and improved construction, using moisture to maintain low atmospheric temperature without the use of ice.

The object of the invention is the provision of novel and improved means for supplying moisture over the top and down the exterior of the food-compartment, so as to maintain a comparatively low temperature, without using ice, and providing an efficient, sanitary and insect proof means for preserving perishable foods during hot weather.

A further object is the provision of such a refrigerator providing for a free circulation of air into and out of and within the refrigerator, to keep the contents cool and wholesome.

With the foregoing and other objects in view, which will be apparent as the description proceeds, the invention resides in the construction and arrangement of parts hereinafter described and claimed, it being understood that changes can be made within the scope of what is claimed without departing from the spirit of the invention.

The invention is illustrated in the accompanying drawings, wherein:—

Figure 1 is a perspective view of the refrigerator.

Fig. 2 is a plan view thereof with the water receptacle removed, and the water controlling plate partially removed from its pocket.

Figs. 3 and 4 are vertical sections of the refrigerator taken at right angles to one another.

In carrying out the invention, there is provided an upright frame or rack including the side walls 1 and top 2, which may be made of metal, concrete or other suitable material. The side walls 2 are provided with relatively large openings 3 therein to

provide for the circulation of air therethrough, and said walls are provided on the inner surfaces thereof with horizontal cleats 4 extending across said openings 3 and serving as seats or supports for the shelves 5 which are placed between said walls. Said walls 1 have flanges 6 extending from their vertical edges to retain the ends of the shelves 5 between them, and the walls 1 are preferably provided with an integral bottom shelf 5'. The shelves are preferably provided with slots or openings for circulation of air therethrough, and the front and rear of the refrigerator are open, while the side walls have the openings 3, thereby permitting of free circulation of air into and out of the food compartment within the rack or frame.

The rack or frame is preferably seated within a pan 7 in which the water is caught, to assist in keeping the foodstuff cool.

A fabric covering is provided over the rack or frame, being composed of two sheets 8 of suitable absorbent material, crossing one another, with their intermediate portions secured together in any suitable manner, so that the covering when laid out flat is in the form of an X, the arms thereof providing aprons 9, so that when the intermediate portions of the sheets are placed on the top 2 of the rack, the aprons 9 hang down the walls of the rack, and inclose the food compartment, permitting air to pass through the curtains, and the curtains being readily raised for inserting or removing articles.

The crossing portions of the sheets 8 are secured together, as at 10, providing a pocket 11 having its mouth opening at one edge of the uppermost sheet 8, to receive the plate 12 of metal, concrete, or other suitable material. In order to supply the moisture, a bottle or other receptacle 13 for holding water is placed in an inverted position on the pocket 11 over the plate 12. In applying the covering and receptacle to the frame, the receptacle is first filled with water in an upright position, and the covering then placed in an inverted position over the receptacle, with the plate 12 passing over the mouth of the receptacle. This enables the receptacle to be inverted and the covering to be placed over the rack with the receptacle, thereby preventing the spilling of the water.

In use, the water will seep from the receptacle into the upper portion of the fab-

ric covering, and will pass by capillary attraction and gravity down the curtains 8, so as to inclose the food compartment in a film of moisture, through which the air can circulate to keep the air within the refrigerator at a low temperature, the device being preferably placed within a shady airy location. By the provision of the plates 12 within the pocket 11 over which the inverted water receptacle is placed, this will control the flow of water from the receptacle, so as to avoid the excessive flow of water. Thus, said plate extends across the mouth of the receptacle so as to retard the flow of water, and the upper sheet 8 is pressed underneath the rim of the receptacle against the plate 12, permitting the water to seep from the receptacle underneath the rim thereof over the plate 12, to keep the covering moist, but without excess moisture or waste of water, so that the frequent filling of the receptacle will not be necessary. The plate 12 also facilitates the inverting of the water receptacle onto the rack or frame, without spilling the water, and the plate 12 can be readily removed from the pocket 11 when it is desired to wash the covering. Having thus described the invention, what is claimed as new is:—

30 1. A refrigerator comprising a frame, a porous covering over the frame and resting on the top thereof, said covering having depending side curtains, and an inverted water receptacle having its mouth lowermost and its edge resting on said covering on the top of the frame in order that the water is compelled to seep under the lower edge of the receptacle.

2. A refrigerator embodying a frame, a porous covering over the frame resting on the top thereof and having depending side

curtains, an inverted water receptacle having its edge lowermost and bearing on said covering on the top of the frame, and a plate assembled with the covering and disposed under said receptacle, said plate providing means for holding the covering over the mouth of the receptacle when the receptacle is applied to and removed from the frame. 45

3. A refrigerator embodying a frame, a porous covering thereon having depending side curtains and a plurality of sheets at the top, a plate disposed between said sheets, and an inverted water receptacle to bear on 50 said covering over said plate.

4. A refrigerator embodying a frame, a porous covering thereon having depending side curtains, and a pocket above the frame, a plate insertible in said pocket, and an inverted water receptacle to bear on 55 said pocket over said plate.

5. A refrigerator embodying a frame, two sheets of porous material crossing one another to bear on the frame and provide 60 depending side curtains, the crossing portions of the sheets being secured together to form a pocket opening at the edge of one sheet, a water receptacle to be placed on 65 said pocket in an inverted position, and a water-controlling plate insertible in said pocket to facilitate the inverting of the receptacle and to control the flow of water therefrom to the curtains.

In testimony whereof I have signed my 70 name to this specification in the presence of two subscribing witnesses.
